UNITED STATES PATENT OFFICE.

ELWOOD GRUBB, OF TALLEYRAND, IOWA.

DESIGN FOR A WEAR-PLATE FOR VEHICLES.

SPECIFICATION forming part of Design No. 34,007, dated January 29, 1901.

Application filed January 3, 1901, Serial No. 42,026. Term of patent 14 years.

To all whom it may concern:

Be it known that I, ELWOOD GRUBB, a citizen of the United States, residing at Tallyrand, in the county of Keokuk and State of Iowa, have invented and produced a new and useful Design for Wear-Plates for Vehicles, of which the following is a specification.

My invention relates to new and original designs in wear-plates for vehicles.

In the accompanying drawing the figure is a perspective view of a wear-plate, showing my new design.

As shown in said drawing, my design consists of a plate having a plain flat surface 1, the side members 2, the triangular bends 3,

and the divergent arms 4, each provided with a series of apertures 5. The surface 1 and the members 2 project outward from the arms 4, as shown in the drawing.

Having thus described my new design, what I claim is—

The design for a wear-plate for vehicles, as shown and described.

In testimony whereof I have hereunto set my hand in presence of two subscribing witnesses.

ELWOOD GRUBB.
